(57) CLAIM

The ornamental design for a frozen treat kit, as shown and described.

DESCRIPTION

FIG. 1 is a front, side and top perspective view of a frozen treat kit showing my new design;

FIG. 2 is a front view of FIG. 1;

FIG. 3 is a side view of FIG. 1;

FIG. 4 is a top view of FIG. 1 with the stabilizing bar and grip removed for ease of illustration;

FIG. 5 is a bottom view of FIG. 4;

FIG. 6 is a front view of the frozen treat grip, shown removed from the kit of FIG. 1 for completeness of illustration;

FIG. 7 is a side view of FIG. 6; and,

FIG. 8 is a bottom, front and side perspective view of the frozen treat grip of FIG. 6, shown in its environmental use.

The broken lines shown on FIGS. 1, 2, 3, 6 and 8 are for the purpose of illustrating unclaimed portions of the frozen treat kit and form no part of the claimed design.
